ELECTRICAL SPARKING DEVICE.

1,093,318.

Specification of Letters Patent. Patented Apr. 14, 1914.

Application filed August 5, 1912. Serial No. 713,460.

To all whom it may concern:

Be it known that I, WILLIAM J. CUNNINGHAM, a citizen of the United States, and a resident of Toledo, in the county of Lucas and State of Ohio, have invented a certain new and useful Electrical Sparking Device; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 My invention relates to electrical sparking devices of the type in which the contact between two or more electrodes is broken by magnetic action.

In the use of devices of this class considerable difficulties have been encountered, principal among them being, the rapid vibrating or repeated contacting of the electrodes when the timer circuit is closed, which injures the electrode points and causes deleterious 20 sparking at the timer; the inability to secure a sufficiently rapid sparking for use in connection with high speed engines; the necessity of keeping the sparking devices dry and in a comparatively cool place, and 25 the inability of securing a single strong flash or spark at each contact of the timer.

The primary object of my invention is the provision of an improved sparking device of this character which is simple and inexpensive 30 in its construction, efficient in its operation and designed to overcome the defects and objections above noted, whereby to enhance the practicability and commercial value of such devices.

40 A further object of the invention is to provide a sparking device of this character which is so constructed as to prevent the possibility of a short circuit occurring between the casing thereof and the engine casing both of such parts being on one side of 45 the circuit, thus preventing short circuiting of the device when in use.

A further object of the invention is the provision of means which is automatically operable to prevent a multiple or vibratory contacting of the electrodes at each circuit closing period and a consequent arcing at the timer contacts, which latter is due to the vibratory or rapid intermittent contacting 50 of the electrodes, thus prolonging the lives

of both the timer contacts and the electrode points.

A further object of the invention is the provision of means which is automatically operable by compression within the cylinder 60 to prevent a multiple contacting of the electrodes when the timer circuit is closed and for assisting the magnetic means in effecting a quick separation of the contact points.

A further object of the invention is the provision of means which will not act to break the contact between the electrodes upon the energizing of the electromagnet but will permit a thorough energizing of the electromagnet and sparking circuit before 70 the contact between the electrodes is broken, whereby to produce a strong spark and a quick breaking of the contact between the electrodes, thus facilitating the use of the device in high speed engines. 75

A further object of the invention is to so form the armature that the magnetic influence of the electromagnet thereon when energized is concentrated adjacent the point of greatest movement of the armature, 80 whereby to facilitate a rapid action of the same for high speed purposes.

A further object of the invention is the provision of a loose roller contact part on one of the electrodes which is turned slightly 85 at each sparking operation by reason of the electrode contacts having a wiping action when making or breaking contact, thus producing a greater flash or arc than is possible with the make and break contact system 90 ordinarily employed, and effects a self-cleaning of the points and the presenting of a new or clean surface at each contact.

Further objects and advantages of the invention will be apparent from the following 95 description.

The invention is fully described in the following specification, and while, in its broader aspect, it is capable of embodiment in numerous forms, a preferred embodiment 100 thereof is illustrated in the accompanying drawings, in which,—

Figure 1 is a central longitudinal section of a sparking device embodying the invention. Fig. 2 is an enlarged detail of a part 105 of the electromagnet. Fig. 3 is a top plan view of the armature and its carrying parts removed from the shell. Fig. 4 is a bottom plan view of the movable electrode carrying part, with the electrode in section, and Fig. 110

5 is a side elevation of the electrode carrying portion of the device and the associated operating parts with portions in section.

Referring to the drawings, 1 designates 5 a shell, preferably of metal, or may be of any suitable material, within the outer end portion of which is mounted an electromagnet, of which 2 is the core and 3 the encircling coil. The core 2 preferably comprises a plurality of soft iron wires, as it is found in practice that with such construction the rapid rise and fall of the magnetism necessary to the efficient and satisfactory operation of apparatus of this character is 10 better taken care of than if a solid iron core is employed.

The spool 4 within which the core is disposed and around which the coil is wound, may be of any suitable construction, and is 20 shown as having its outer end provided with an outwardly projecting annular flange 5, which fits into a registering flanged opening in the outer end of the shell. A terminal-post 6 is suitably anchored within the 25 spool flange 5, being insulated therefrom in any suitable manner, and has the terminal binding-nuts 7, 7 threaded to its outer end. One end of the coil wire is attached to the terminal post 6, while the other end of 30 the coil, which terminates at the opposite end of the electromagnet, has electrical connection with a spring-finger 8, which extends at least partially across the lower end of the magnet. The spring 8 and the connection between it and the coil end are insulated both from the shell 1 and spool 4, as best shown in Fig. 2, so that the current will not be short-circuited to the shell. The electromagnet is rigidly suspended 35 40 within the upper or outer end of the shell by an insulating nut 9, which is threaded over the post 6 before the nuts 7 are placed thereon and has its outer edge projected over the flange at the end of the shell, as 45 shown in Fig. 1.

A plug 10 is threaded into the inner or open end of the shell 1, and has its outer end portion reduced and adapted to thread into the customary spark plug opening in 50 an engine cylinder. This plug is provided longitudinally therethrough with an opening 11, and has its free end, or that which is intended to project within an engine cylinder, provided at one side thereof with 55 an extension 12, which forms the fixed electrode of the device, being provided for such purpose adjacent to its end with a laterally projecting contact point 13.

The movable electrode of the device comprises the bar 14, which projects longitudinally through the opening 11 of the plug 10 and is provided near its inner end with a ball or spherically bearing part 15, which is mounted within a socket provided in the 65 center of the bearing member 16 through

which the electrode 14 projects, thus adapting such electrode to have universal pivotal movements relative to said member. The ball 15 is held to its seat within the socket by a removable plug 17, which is threaded 70 into the member 16 and forms a part of the ball holding socket. The member 16 has an annular flange 18 projecting therefrom and insulatingly clamped at its outer edge between two holding rings 19 and 20, 75 the latter of which is threaded into an annular flange depending from the former. The clamp which is thus formed is firmly secured within the inner or open end portion of the shell 1 in spaced relation to the electromagnet by reason of the outer end portion of the ring 19 being clamped between an annular internal shoulder 21 in the shell 80 and the inner end of the plug 10.

The outer end of the electrode 14 is preferably provided with a loose roller contact part 22, which is intended to make peripheral contact with the end of the point 13 on the fixed electrode 12. The roller 22 preferably has a slight wiping action against 85 the point 13 when making and breaking contact therewith so as to cause it to turn slightly upon the bar 14 at each sparking operation, thus causing its point of contact with the point 13 to constantly change and 90 effecting a self-cleaning of the contact parts.

An armature 23 is mounted within the space between the movable electrode carrying part 16-18 and the electromagnet, being hinged adjacent to one side thereof to 100 a lug 24 rising from the part 18. This armature is preferably of disk form and is attracted to the magnet upon an energizing of the same. In order that the armature may respond quickly to a magnetizing of 105 the magnet, its free end portion, or that which is more remote from its hinge, is made of steel or other suitable material which is highly sensitive to magnetic action while the inner or hinged end portion thereof is made of brass or other suitable material which is less sensitive to such action. These materials are respectively designated in Fig. 3, by the letters *a* and *b*. This form of armature very materially enhances the 110 efficiency of the device for use in high speed engines. The armature 23 is normally held in its lowered or seated position by the action thereon of the spring finger 8 which bears at its free end against the upper side 115 of the armature adjacent to its free or outer end. This spring also serves as an electrical connection between the coil and movable electrode 14, as the current is carried thereby to the armature and thence to the movable electrode, the upper or inner end of which works into an opening 25 in the central portion of the armature and has contact with the part *a* thereof.

In order to cause a movement of the ar- 120

5 mature which is responsive to an energizing of the magnet to impart a rocking movement to the electrode 14 to break contact between the two electrodes, a pin 26 projects laterally from the inner end of the electrode bar 14 away from the armature hinge 24 and has its free end working loosely through a loop 27, which depends from the under side of the armature adjacent to its free end. It is evident that the bar 14 and pin 26 cooperate to form an electrode of bell-crank lever form, and that a rising movement of the armature will cause the loop 27 to act on the pin 26 to move it and the bar 14 to effect a breaking of contact between the electrodes.

10 It will be noted that some play is provided between the lower end of the loop and the pin 26 so that the loop will not engage 20 the pin and effect a breaking of the contact of the electrodes until the armature has made a portion of its attracted movement. The purpose of this is to enable the coil to become thoroughly energized before the 25 breaking of contact between the electrodes so that a current of maximum strength will flow through the electrodes at the time of breaking contact, thus creating an arcing flash of greater intensity than would otherwise be the case. Such connection also enables the armature to gather some momentum before picking up and moving the electrode, so that the contact breaking of the electrodes, when accomplished, will be 30 quicker than if the armature acts on the pin as soon as it starts its attracted movement.

35 The movable electrode is normally held in contact with its companion by the action on its inner end of a spring finger 28, which is attached at one end to a post 29, which rises from the side of the flange 18 adjacent to the armature 23, and has its free end bearing against the inner end of the electrode bar 40 45 14 in a direction to force its outer end into lateral contact with the point 13 of the fixed electrode.

50 The flange 18 is provided beneath the free end portion of the armature 23 with a cylinder 29 in which a plunger 30 works. This plunger has a needle-valve 31 provided on its lower side and adapted to seat in and close a small orifice 32 in the outer end of the cylinder casing. This orifice has its 55 outer end in connection through the hollow of the plug 10 with the compression end of an engine cylinder to which the device is attached; so that pressure within the engine cylinder is permitted to pass to the interior 60 of the cylinder 29, when the valve 31 is unseated, and act against the lower side of the plunger 30. A stem 33 rises from the top of the plunger 30 through the upper end of the cylinder casing and has its outer or 65 free end attached to the armature 23 to

cause the plunger to move with the armature. When the armature is in its normal unattracted position the plunger 30 is lowered sufficiently within its cylinder for the valve 31 to seat in and close the orifice 32. 70 Upon the initial rising or attracted movement of the armature, and before the electrode 14 has been moved to break contact with its companion, the valve 31 is raised from its seat in the orifice to permit the 75 pressure, which is present in the engine cylinder, to enter the small cylinder 29 and act upon the plunger 30 to assist the electromagnet in raising the armature, thereby securing a quicker and more powerful breaking movement of the electrodes than would otherwise be the case. In addition to this, the plunger 30 maintains the electrodes separated until the pressure within the cylinder has been exhausted or diminished, thus preventing 80 the objectionable vibrating and repeated contacting of the electrodes and consequent arcing at the timer contacts at each 85 sparking operation. The plunger stem and armature, are shown in the present instance, 90 as being connected by inserting the outer end of the plunger stem into an opening 34 in the armature and providing such opening and the stem with interengaging portions, as indicated at 35 in Figs. 3 and 5. The 95 stem may be moved from engagement with the armature by moving it laterally therein into an enlarged portion in the opening 34.

To facilitate a proper relative positioning of the plug 10 and movable electrode holding member, when such parts are assembled, a stud 36 projects inwardly from the inner end portion of the plug 10 into a socketed post 37, which projects downward from the under side of the member 18. The post 37 100 is insulated from said member to prevent a short-circuiting of the current to the inner end portion of the plug 10.

105 In the use of my improved sparking device each closing of the timer circuit, which is in series with the electromagnet, causes an electric current to flow through the coil 3, spring 8 and armature 23 to the electrode bar 14 and thence through the fixed electrode 12 and cylinder casing back to the 110 timer in a manner well understood in the art. Upon an energizing of the electromagnet the armature 23 is raised or swung toward the magnet due to the magnetic influence of the magnet thereon, thus raising the 115 plunger 30 to unseat the valve 31. The unseating of the valve 31 is effected as soon as the armature begins its responsive movement, thus opening the cylinder 29 of the 120 sparking device to the compression end of the engine cylinder to permit the pressure in the latter to enter the former and act on the plunger 30 to assist the electromagnet in the further raising of the armature. It 125 will be evident that this compression oper- 130

ated means, in conjunction with the magnetic action of the electromagnet, imparts a quick and powerful opening movement to the armature and a consequent quick breaking of the contact between the electrodes. 5 As the armature loop 27 is normally spaced from the electrode pin 26, the electrode will not be moved to break contact with its companion until the armature has traversed a 10 part of its opening or responsive movement, thus permitting a thorough building up of the current in the coil and electrodes before the breaking of contact, and also enabling the armature to gain momentum before moving 15 the electrode so that the contact breaking movements of the electrode will be quicker than would otherwise be the case. The compression actuated plunger 30, in addition to assisting the electromagnet in 20 obtaining a quick opening movement of the armature, also serves to maintain the armature and movable electrode in their moved or attracted positions until the compression within the engine cylinder has become exhausted or diminished to a predetermined 25 extent, preventing the vibrating of the movable electrode and consequent repeated sparking at both the sparking device and timer contacts when the sparking circuit is closed. This is a very valuable feature of 30 the device as the repeated sparking at the contact points causes such a burning and wearing of the contacts as to render necessary a frequent replacing thereof.

35 I wish it understood that the invention is not limited to any specific construction or arrangement of the parts, or necessarily to the use in combination of the parts described, except in so far as such limitations 40 are specified in the claims.

Having thus described my invention, what I claim as new and desire to secure by Letters Patent, is,—

1. In an electrical sparking device, an 45 electromagnet, an armature responsive thereto, a fixed electrode, a movable electrode movable by a responsive movement of the armature to break contact with the fixed electrode, and compression actuated means 50 for assisting the electromagnet in moving the armature to break the contact.

2. An electrical sparking device having 55 fixed and movable electrodes, and both compression and electrically operated means for assisting in imparting movements to the movable electrode to cause it to break contact with its companion.

3. An electrical sparking device having 60 relatively movable electrodes, compression actuated means for imparting relative movements to the electrodes, said means normally standing in one position and being inoperative when in such position, and electrically operated means for initially moving said 65 first means from normal position.

4. The combination with an engine cylinder, of an electrical sparking device having relatively movable electrodes, a second cylinder in communication with the combustion end of the engine cylinder, means normally closing the communication between said cylinders and operable by engine cylinder compression to impart contact breaking movements to one of said electrodes when said communication is opened, and electrical 75 means for controlling the opening of the communication between the two cylinders.

5. The combination with an engine cylinder, of an electrical sparking device having relatively movable electrodes, a second cylinder in communication with the engine cylinder, means having a part working in said second cylinder and normally closing the communication between the two cylinders and operable by engine cylinder compression 85 to break contact between the electrodes when the communication between the cylinders is open, and electrical means for controlling the opening of such communication.

6. An electrical sparking device having 90 relatively movable electrodes, an electromagnet, means responsive to the electromagnet for moving one of said electrodes, means controlled by a movement of said first means and operable by fluid pressure to assist the 95 electromagnet in moving said first means.

7. An electrical sparking device having movable electrodes, an electromagnet, and an armature responsive to the electromagnet and adapted to break contact between the 100 electrodes when moved in one direction, and fluid pressure operated means for acting on said armature to assist the electromagnet in moving the armature to break contact between the electrodes.

8. The combination with an engine cylinder, of an electrical sparking device having relatively movable electrodes, an electromagnet, an armature responsive to an energizing of the electromagnet for moving one of said 110 electrodes to break contact with its companion, and means having a part in connection with the armature and movable by compression within the cylinder after the initial contact breaking movement of the armature 115 to assist the electromagnet in imparting electrode contact breaking movements to the armature.

9. The combination with an engine cylinder, of an electrical sparking device having 120 relatively movable electrodes, an electromagnet, an armature connected to one of said electrodes and responsive to an energizing of the electromagnet to move said electrode to break contact with its companion, a chamber having communication with the compression end of the plunger, a cylinder movable in said chamber and attached to the armature and operable upon an initial responsive movement of the armature to admit en- 125 130

gine cylinder pressure to said chamber to act upon the plunger to assist the electromagnet in moving the armature to break contact between the electrodes.

- 5 10. An electrical sparking device having relatively movable electrodes, an electromagnet, means responsive to an energizing of the electromagnet for breaking contact between the electrodes, and fluid pressure operated means for holding the electrodes separated for predetermined intervals after each contact breaking action thereof.

- 10 15. The combination with an engine cylinder, of an electrical sparking device having relatively movable electrodes, an electromagnet, means responsive to an energizing of the electromagnet for breaking contact between the electrodes, and means actuated by cylinder compression for retaining electrodes spaced after their contact breaking action until the pressure within the cylinder has been reduced a predetermined extent.

- 15 20. The combination with an engine cylinder, of an electrical sparking device having relatively movable electrodes, an electromagnet, means responsive to an energizing of the electromagnet for effecting a breaking of contact between the electrodes, and means actuated by compression within the cylinder for maintaining the electrodes spaced after contact is broken therebetween and until the pressure within the cylinder has been reduced, said latter means being inoperative until said first means has begun its responsive movement.

- 20 25. An electrical sparking device having relatively movable electrodes, means intermittently operable to break contact between the electrodes, and fluid pressure operated means for holding the electrodes separated for predetermined intervals after each contact breaking action thereof.

- 25 30. The combination with an engine cylinder, of an electrical sparking device having relatively movable electrodes, means for relatively moving the electrodes to break contact therebetween, and means actuated by cylinder compression for retaining the electrodes spaced after their contact breaking action until the pressure within the cylinder has been reduced a predetermined extent.

- 30 35. An electrical sparking device having relatively movable electrodes, electrical means intermittently operable to relatively move the electrodes to break contact, and means movable with a part of said first means and automatically operable to assist said means in its electrode moving action and being inoperative when said means is in normal position.

- 35 40. The combination with an engine cylinder, of an electrical sparking device having relatively movable electrodes, means operable to effect an intermittent breaking of contact between the electrodes, a chamber

having communication with the compression end of the cylinder, a member movable in said chamber and attached to said electrode moving means for movements therewith and operable upon an initial electrode breaking movement of said means to admit engine cylinder pressure to said chamber to act upon the member to assist said means in breaking contact between the electrodes.

40 45. 17. The combination with an engine cylinder, of an electrical sparking device having relatively movable electrodes, electrically energized means normally standing in one position and intermittently operable to break contact between the electrodes, a chamber having communication with the compression end of the cylinder, a plunger movable in said chamber and attached to said means for movement therewith and adapted to close the communication between the chamber and cylinder when the means is in its normal position, said plunger being acted on by fluid pressure from the cylinder to assist said means in breaking contact between the electrodes when the plunger has been moved from its normal position by said means.

50 55. 18. In an electrical sparking device, an electromagnet, a fixed electrode, an electrode mounted for rocking movements and having a finger projecting therefrom transversely of its rocking axis, and an armature responsive to the electromagnet and having a part in loose sliding engagement with said finger to impart contact breaking movements to the movable electrode when the armature is moved upon an energizing of the electromagnet, the electromagnet coil and the electrodes being in circuit.

60 65. 19. In an electrical sparking device, an electromagnet, a fixed electrode, a pivotally movable electrode having a finger projecting from its inner end transversely of its rocking axis, an armature responsive to the electromagnet and having a loop on one side thereof through which said finger loosely projects for moving the electrode to break contact with its companion when the armature is moved responsive to said magnet, and means acting to normally hold the electrodes in contact.

70 75. 20. In an electrical sparking device, a shell, an electromagnet disposed therein and having one terminal of its coil projecting from the shell, a fixed electrode projecting from one end of the shell and having an opening therethrough, a movable electrode mounted within said opening for universal pivotal movements, an armature disposed within the shell between the electrodes and the electromagnet and responsive to the latter, connection between the armature and the movable electrode to impart movements from one to the other, and means acting on the armature to normally hold it retracted

from the electromagnet and coöperating with the armature to electrically connect a terminal of the electromagnet coil and the movable electrode, said shell and fixed electrode forming one side of the sparking circuit.

21. In an electrical sparking device, a shell having an end projected and forming a fixed electrode, an electromagnet disposed within the end portion of the shell opposed to said electrode, a bearing member fixedly mounted within the shell intermediate said electromagnet and having a bearing therein, an armature disposed between said member and electromagnet and pivotally attached to said member at one side of its bearing, said armature being responsive to the electromagnet, means yieldingly retaining the armature in one position of its movement, a movable electrode mounted in the bearing of said member and having its outer end portion capable of contacting with the fixed electrode and its inner end portion provided with a laterally projecting finger having loose connection with said armature where-

by a responsive movement of the armature rocks the movable electrode to break contact with its companion, the electromagnet coil and the movable electrode being in electrical connection and said shell and fixed electrode forming one side of the sparking circuit.

22. In an electrical sparking device, a fixed electrode and a movable electrode mounted for universal movements, means intermittently operable to move the movable electrode to break contact with its companion, and a spring acting on the movable electrode in a direction different from the action of said means thereon whereby the movable electrode is caused to have a slight wiping contact-breaking movement when moved by said means.

In testimony whereof, I have hereunto signed my name to this specification in the presence of two subscribing witnesses.

WILLIAM J. CUNNINGHAM.
